(57) CLAIM

The ornamental design for an electronic device, as shown and described.

DESCRIPTION

FIG. 1 is a top perspective view of an electronic device showing my new design;

FIG. 2 is a bottom perspective view thereof;

FIG. 3 is a top view thereof;

FIG. 4 is a bottom view thereof;

FIG. 5 is a back view thereof;

FIG. 6 is a front view thereof; and,

FIG. 7 is a left side view thereof.

The right side view thereof is a mirror image of the left side view as depicted in FIG. 7.

The portions shown in broken lines are included for illustrative purposes only and form no part of the claimed design.
